UNITED STATES PATENT OFFICE

HARRY M. MATHERS, OF PORTLAND, OREGON

CIRCULAR DATE CALENDAR

Application filed November 2, 1931. Serial No. 572,605.

My invention relates to circular date calendars.

The object of my invention is to provide a practical and economical annular calendar adapted, by means of a radial hand, to indicate successively without auxiliary devices, the current day of the week and month as it occurs, regardless of the differences in the number of days in the respective months or 10 the variations of the days of the weeks corresponding thereto.

A further object of my invention is to provide an annular calendar adapted to be combined with a clock provided with a third or 15 calendar hand operated by the clock mechanism, thereby to provide full information as to the time of the day, week and month by means of a single instrument.

Heretofore, the combination of a calendar and clock has not been satisfactory for the 20 reason that the months do not have equal numbers of days, and hence the calendar hand of the clock must be provided with an irregular rate of rotation corresponding to the 25 number of days in the successive months; this requires complicated and expensive mechanism. Further, such calendar clocks as have been provided have been incapable of 30 indicating the days of the week, since they vary with respect to the days of the month, and it is impossible to provide for this purpose a simple but complete calendar adapted to serve for all the months.

I attain my above objects in combination 35 with a calendar dial and a calendar hand, a series of annular calendar sheets adapted to be placed on said dial, one over the other, each sheet bearing the numerals of the month which it represents, the numerals representing 40 the first days of the underlying consecutive calendar sheets being arranged to follow directly, respectively, the numeral representing the last day of the month on the overlying calendar sheet, whereby, upon the advancement of said hand and the removal of 45

the top calendar sheet the numeral representing the first day of the month on the underlying calendar sheet will be in registration with the advanced position of the said hand.

A still further object of my invention is to 50 provide a clock adapted to have my calendar mounted thereon in a convenient and economical manner and so constructed as to permit the ready removal of the sheet carrying the calendar of the preceding month.

These and other incidental features of my 55 calendar, the details of construction and mode of operation are hereinafter fully described with reference to the accompanying drawings.

In the drawings:

Fig. 1 shows an elevation of a clock provided with a calendar hand and a lateral, circumferential flange upon which my calendar is mounted;

Fig. 2 shows a central vertical section of the 65 same;

Fig. 3 shows an elevation of the clock with my calendar removed;

Fig. 4 shows an enlarged detached view of 70 my calendar with one sheet folded back to expose the arrangement of the underlying sheet;

Fig. 5 shows a modification of my invention in which the front of the clock is provided with a hinged cover adapted to conceal 75 the underlying calendar sheets, which in this embodiment are printed upon relatively stiff cards;

Fig. 6 shows a reduced elevation of the same with the cover removed;

Fig. 7 shows a side elevation of the clock with the cover open and illustrates how the 80 calendar cards are removable;

Fig. 8 shows an enlarged side elevation of 85 this modification partly in section and illustrates how the calendar cards are arranged within the cover; and

Figs. 9, 10 and 11 show respective calendar cards for the months of January, February and March and further illustrate the relative 90

arrangement of the first day of the respective months.

Referring now to Figs. 1 to 4, *a* represents a clock provided with a third or calendar hand *b*, adapted by a suitable modification of the clock mechanism to make one complete revolution in thirty-one days.

The dial *c* of the clock is provided with a lateral marginal flange *d*, adapted to have secured thereon a series or pad of annular monthly calendar sheets *e* preferably printed upon thin paper and super-imposed one on the other.

The monthly calendar sheets *e* are preferably secured on a section of stiff cardboard *f* or the like by suitable adhesive so as to be conveniently removable, and the cardboard section *f* is in turn removably secured on the flange *d*, preferably by snap fasteners *g*, in order to be conveniently removable and to permit replacements by a new set of sheets, when the old ones are exhausted.

The monthly calendar sheets *e* are circumferentially divided into 31 spaces which for January and other months having thirty-one days are numbered consecutively from 1 to 31, as in Figs. 1, 9 and 11. For other months having less than thirty-one days, the remaining spaces are left blank, as in Figs. 4 and 10.

For a given month, the names of the days of the week are placed opposite the corresponding days of the month, for example, January, shown in Fig. 1. Figs. 4, 10 and 11 illustrate the calendar sheets for February and March.

The calendar sheets *e* are placed one over the other, so that the numerals representing the first days of the underlying and consecutive calendar sheets are arranged to follow directly, respectively the numerals representing the last day of the month on the overlying sheet, as illustrated at *e'*, and *e2* in Fig. 4, and at *e3*, *e4*, and *e5* in Figs. 9, 10, and 11.

Operation.—When my calendar is assembled and assuming the present month to be January, 1931, as illustrated in Fig. 1, the calendar hand will move one space each day until it reaches and passes January 31st. The January sheet will then be torn off, see Fig. 4, exposing the underlying February sheet, which is so positioned that February first is opposite the calendar hand. Similarly, when the 28th day of February is passed and the February sheet is torn off, the March sheet will be exposed, the first day of which is positioned one day in advance of February 28th and will lie opposite the calendar hand. The sheets of the remaining months are likewise arranged so that as each month passes and the old sheet is torn off, the first day of the succeeding month lies opposite the calendar hand.

Thus, upon the removal of the top calendar sheet and the advancement of said hand, the

numeral representing the first day of the month on the underlying calendar sheets will be in registration with the advanced position of said hand.

By these means, I have provided a calendar adapted in combination with a clock or similar device, to indicate by means of a regularly rotated calendar hand, and without adjustments or auxiliary devices, the current days of the weeks and months as they occur.

A further advantage of my calendar is, even though the user neglects to tear off last month's sheet for a few days, the hand will continue to move, so that when the sheet is torn off, the hand will be pointing to the present day, since the days of the month on the underlying sheet follow in successive order. Also, if the clock mechanism should stop, the calendar hand *b* may be readily reset at the time the clock is started by means of a setting pin *g*, see Fig. 2.

Of course, as illustrated, my calendar is most conveniently used in combination with a clock and an automatically operated hand, but may be used as well solely as a calendar, in which case the hand may be either automatically operated or set manually every day by the owner.

Figs. 5 to 11, inclusive, illustrate a modification of my calendar, in which the individual calendars are composed of relatively stiff cards 2, rather than the flexible sheets heretofore described.

Further, the clock is provided with a frame-like cover 3 hinged at the bottom, as at 4, to a perimetrical lateral flange 5 provided on the clock body 6. The clock dial is provided with an outstanding circumferential flange 7 on which the calendar cards 2 are concentrically arranged and supported, see Fig. 8. The cover 3 is provided with side sections 9 so that when the cover section 3 is closed, as illustrated in Fig. 8, the edges of the underlying cards 2 are concealed and all that is visible will be the calendar card of the current month. A latch 10 is provided at the top of the flange 5 for holding the cover in closed position. Further, by these means, the cards 2 are housed within the cover 3 so that their edges are protected from wear. A transparent cover, not shown, for the face of the calendar cards may be provided, either secured to the cover or arranged loosely therein of the same shape and size as the calendar cards.

In such modification, instead of discarding a calendar card after the month has passed, it is moved to the rear of the compartment and serves to hold the current calendar card positioned against the cover.

Further, I propose to imprint upon the reverse side of each calendar card the next successive month so that the period for which my calendar may be used without replacements will be doubled, that is, twelve cards

will then serve for 24 months instead of only 12.

I claim:

1. In combination with a clock mechanism including an auxiliary calendar hand and a housing provided with a circumferential lateral flange about the clock's face, a series of annular calendar sheets adapted to be placed on said flange one over the other, each sheet bearing the numerals of the month which it represents, the numerals representing the first days of the underlying consecutive calendar sheets being arranged to follow directly, respectively, the numeral representing the last day of the month on the overlying calendar sheet, whereby upon the advancement of said hand and the removal of the top calendar sheet, the numeral representing the first day of the month on the underlying calendar sheet will be in registration with the advanced position of the said hand.

2. In combination with a calendar dial and a calendar hand, a series of annular calendar sheets adapted to be placed on said dial, one over the other, each sheet bearing the numerals of the month which it represents, the numerals representing the first days of the underlying consecutive calendar sheets being arranged to follow directly, respectively, the numeral representing the last day of the month on the overlying calendar sheet, whereby, upon the advancement of said hand and the removal of the top calendar sheet the numeral representing the first day of the month on the underlying calendar sheet will be in registration with the advanced position of the said hand.

3. In combination, a case comprising a body adapted to have centrally placed therein a dial and to provide an annular space about such dial, a hand carried by said dial and rotatable thereon, a cover hinged to the case and adapted to cover the entire face thereof, a series of calendar sheets adapted to be placed in said annular space, one over the other, each sheet bearing the numerals of the month which it represents, the numerals representing the first days of the underlying consecutive calendar sheets being arranged to follow directly, respectively, the numeral representing the last day of the month on the overlying calendar sheet, whereby upon the advancement of said hand and the removal of the top calendar sheet, the numeral representing the first day of the month of the underlying calendar sheet will be in registration with the advanced position of the said hand.

4. In combination, a case comprising a body adapted to have centrally placed therein a dial and to provide an annular space about such dial, a hand carried by said dial and rotatable thereon, an open cover hinged to the case and adapted to cover a circum-

ferential portion of said annular space, a series of calendar sheets adapted to be placed in said annular space, one over the other, each sheet bearing the numerals of the month which it represents, the numerals representing the first days of the underlying consecutive calendar sheets being arranged to follow directly, respectively, the numeral representing the last day of the month on the overlying calendar sheet, whereby upon the advancement of said hand and the removal of the top calendar sheet, the numeral representing the first day of the month of the underlying calendar sheet will be in registration with the advanced position of the said hand.
